CLAIM

The ornamental design for a cable organizer, as shown and described.

DESCRIPTION

FIG. 1 is a top front right perspective view of a cable organizer with a clip positioned on the left thereof, including a cable and additional cable clips during use;

FIG. 2 is a top front right perspective view of the cable organizer of FIG. 1, without the cable;

FIG. 3 is a front elevation view thereof;

FIG. 4 is a rear elevation view thereof;

FIG. 5 is a top plan view thereof;

FIG. 6 is a bottom plan view thereof;

FIG. 7 is a left elevation view thereof; and,

FIG. 8 is a right elevation view thereof.

Portions of the claimed design are shown separated and bound by a bracket to indicate indeterminate length.

The broken lines shown in the drawings are included to illustrate environment portions of the cable organizer that form no part of the claimed design.
